(57) **CLAIM**

We claim the ornamental design for a photovoltaic device, substantially as shown and described.

DESCRIPTION

FIG. 1 is a top perspective view of a photovoltaic device in accordance with the present design.

FIG. 2 is a left side elevational view of the photovoltaic device of FIG. 1.

FIG. 3 is a right side elevational view thereof.

FIG. 4 is a front edge elevational view thereof.

FIG. 5 is a back edge elevational view thereof.

FIG. 6 is a top plan view thereof.

FIG. 7 is a bottom plan view thereof.

FIG. 8 is an enlarged view of area "8" of FIG. 6; and,

FIG. 9 is an enlarged view of area "9" of FIG. 6.

Any broken lines in the figures represent portions of a photovoltaic device which form no part of the claimed design.
